CLAIM

The ornamental design for a reversing lever for ratchet wrench, as shown and described.

DESCRIPTION

FIG. 1 is a front top perspective view of a reversing lever for ratchet wrench showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an exploded perspective view thereof;

FIG. 9 is another exploded perspective view thereof; and, FIG. 10 is a cross-sectional view taken along line 10-10 of FIG. 2 thereof.

The broken lines illustrate portions of the reversing lever for ratchet wrench and form no part of the claimed design.

1 Claim, 10 Drawing Sheets(56)
